UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed March 12, 1923. Serial No. 624,332.

To all whom it may concern:

Be it known that I, HARRY A. DAVIS, a citizen of the United States, and a resident of Hopedale, county of Worcester, State of Massachusetts, have invented an Improvement in Feeler Mechanism for Looms, of which the following description, in connection with the accompanying drawing, is a specification, like characters on the drawing representing like parts.

This invention relates to looms provided with a feeler mechanism arranged to co-operate with or feel intermittently the filling in the working shuttle and, when substantial exhaustion thereof has been detected, to initiate a desired change in the operation of the loom, such as the automatic replenishment of the working filling.

The feeler mechanism is usually arranged to co-operate with the filling in the shuttle on every other pick, but the co-operation of the feeler mechanism with the filling is unnecessary until the filling is approaching substantial exhaustion. Moreover, with certain kinds of filling and under certain conditions the continued intermittent action of the feeler mechanism is objectionable and injurious.

While means have heretofore been provided to maintain the feeler mechanism inactive for relatively long periods and to render it active during relatively short recurrent periods until the filling has approached substantial exhaustion, such means have left the feeler member, during the periods of inactivity, in the same position. But the diameter of the mass of the working filling in the shuttle is constantly being reduced so that the length of movement and the momentum available for moving the feeler member to its inactive position is constantly changing. Consequently, the blow imparted by the filling to the feeler member to move it to inactive position must be more powerful as the mass of filling decreases or the feeler mechanism must remain in active position during the final period when the filling is approaching substantial exhaustion longer than is necessary.

The object of the present invention is to provide a feeler mechanism in which the feeler is held in its forward or inoperative position by a detent device and in which the

detent device is moved bodily rearwardly after the feeler is released and then restored to retracted position after it has been engaged by the feeler so that the feeler is carried to, and during its unreleased or operative position is held at, a position where it is well out of contact with the filling. Consequently, the feeler is not struck by the filling while it is in its unreleased or inoperative position and, consequently, also the minimum extent of movement and power is required to be exerted by the filling to move the feeler into engagement with the detent device, and, consequently, the filling may be drawn off to a point closely approaching substantial exhaustion before the feeler is allowed to remain in normal operative feeling position.

The invention has for its further object to provide a bodily movable carrier for the detent device and means for moving this carrier rearwardly and forwardly at the proper times to effect the desired results.

A further object of the invention is to provide a feeler mechanism for looms wherein the feeler may have short periods of activity and longer periods of inactivity during the weaving operation with the same supply of filling in the shuttle, and when in inactive or inoperative position the feeler shall be withdrawn or moved forwardly to an extent that avoids contact with the filling on a detecting beat.

An important feature of the present invention, therefore, consists of means for withdrawing or moving the feeler away from its feeling position to render it inactive, and to hold it in such withdrawn position during its period of inactivity.

Another important feature of the present invention consists in releasing the feeler from its inoperative position at intervals that it may move to feeling position and detect the condition of the filling in the shuttle, and then withdraw it from such feeling position provided a working supply of filling is detected by the feeler, or permit it to remain in active position in case the feeler detects a near approach to substantial exhaustion, so that on the occurrence of the substantial exhaustion of the filling in the shuttle the feeler may call for a change of filling.

While these broad features of the inven-

tion are applicable to various types of feeler mechanism they are herein shown in connection with a type of feeler mechanism known as the "side-slip" feeler wherein the feeler 5 tends to move lengthwise of the filling carrier, but is restrained from such lengthwise movement by the filling on the filling carrier until the required degree of exhaustion has been reached when the feeler, encountering 10 the smooth surface of the filling carrier, slips therealong and effects initiation of the change in the operation of the loom.

A further feature of the invention, therefore, resides in the combination with the 15 "side slip" feeler of the features of the invention already pointed out.

The nature and objects of the invention will more fully appear from the accompanying description and drawings and will be 20 particularly pointed out in the claims.

The drawings illustrate a simple and preferred embodiment of the invention in connection with a preferred form of "side slip" feeler mechanism, such as illustrated in the 25 patent to Stimpson No. 1,309,226 granted July 8, 1919.

Such a type of feeler mechanism is usually employed in connection with an automatic filling replenishing loom of the well 30 known "Northrop" type. As this type of loom and as the type of feeler mechanism illustrated are both well known and familiar to those skilled in the art it will only be necessary here to describe in detail 35 those features of construction particularly concerned with the embodiment of the present invention.

In the drawings:

Fig. 1 is a top plan view, partially broken 40 away, of the left hand or detecting end of an automatic filling replenishing loom embodying a preferred form of construction of the present invention;

Fig. 2 is a detail, in rear elevation, of a 45 portion of the controller mechanism;

Fig. 3 is a top plan view of the main elements of the feeler mechanism with the feeler in released rearwardly projected position adapted to co-operate in a normal 50 manner with the filling in the active shuttle and with the detent carrier and detent device in forward untripped position;

Fig. 4 is a view similar to Fig. 3 with the 55 detent carrier and detent device in rearward position and with the feeler re-engaged with the detent device;

Fig. 5 is a side elevation, partially in vertical cross section, of the construction in the 60 position shown in Fig. 3;

Fig. 6 is a side elevation, partially in vertical cross section, of the construction in the 65 position shown in Fig. 4;

Fig. 7 is a view similar to Fig. 3, but with the parts in the position assumed when 70 the feeler is in its unreleased or inoperative

position so as to be held well out of contact with the filling;

Fig. 8 is a front elevation of the construction as shown in Fig. 3;

Fig. 9 is a rear elevation of the construction shown in Fig. 3 with the rearward portions of the feeler and plunger cut away.

In the construction illustrated the feeler mechanism is shown mounted at the left hand end of the breast beam 1 of the loom. 75 The lay 2 is shown provided with the shuttle box 3 at the corresponding end of the loom in which is shown boxed the shuttle 4 containing the filling carrier 5 provided with the mass of working filling 6. An opening 7 is provided through the front wall 8 and a similar opening through the front wall of the shuttle to permit the feeler to enter and feel against the filling upon each detecting beat-up of the lay. 85

In the particular construction illustrated a "side slip" feeler mechanism of the general type shown in the patent to Stimpson above mentioned is shown. This feeler mechanism presents a suitable support or bracket 9, usually of cast iron, adjustably secured to the breast beam as by means of one or more bolts 10 extending through the slot 11 in the support into the breast beam 1 or an extension thereof. The feeler consists of a long arm 12 bent at its rearward end to present the feeler tip 13 slotted on its rear face to provide the filling engaging teeth 14. At its forward end the feeler rod 12 slides freely in a guide 15 swiveled at 16 in the support 9. At the rear end of the support the feeler rod extends through a broad passage-way or slot 17 of a slotted guide at the rear of the support. The slot 18 of this guide is closed at the top by a cap plate 19 thus confining the feeler rod against vertical movement. A controller in the form of a sliding plate 20 is mounted for lateral sliding movement in the slot 18 and is itself slotted at 21 to allow for the passage of the feeler rod 12 therethrough. Substantially midway of the support, between the swiveled guide 15 and the controller 20, there is secured to the feeler rod 12 a slide 22 which slides on horizontal slide-ways 23 formed on the top face of the support 9. This slide 22 is adjustably secured longitudinally of the feeler rod and held in position by a nut 24. A spring 25 surrounds the feeler rod between the nut 24 and the swiveled guide 15 and normally tends to project the feeler rod rearwardly. The rearward movement of the feeler rod is limited by the engagement of the slide 22 with the rearward end 26 of the support in which is formed the slot 18. 115 120 125 130

the right with respect to the main body of the rod. As a result of this construction, when the lay beats up, the filling 6 in the working shuttle, when it engages the tip of 5 the feeler and pushes the feeler rod forwardly, tends at the same time to move the feeler tip to the right longitudinally of the filling carrier. So long as the filling is of sufficient mass to engage the teeth 14 of the 10 feeler tip, the resistance thus offered prevents any slipping movement of the feeler tip lengthwise of the filling carrier and the feeler rod is simply pushed forwardly compressing the spring 25 and swinging the 15 slide 22 and swiveled guide very slightly. When the lay beats back the spring 25 moves the feeler rod rearwardly until the slide 22 engages the rear end 26 of the support. When, however, the filling is substantially 20 exhausted so that the bare surface of the filling carrier 5 engages the feeler tip upon the beat-up, the tip is no longer restrained by the filling, but slips to the right along the smooth surface of the filling carrier. This 25 side slipping movement of the feeler is what is utilized to initiate the change in the operation of the loom by transmitting a lateral movement to the right to the controller 20. When the lay beats back the spring 25 projects the feeler rod rearwardly and a depending lug, from the slide 22, riding along the cam surface 27 on the support 9, cams the 30 feeler rod laterally into its normal position.

35 A simple and preferred form of mechanism for transmitting the lateral movement of the controller 20 to effect a change in the operation of the loom is illustrated. A controller rod 28 is pivotally connected to the controller 20 and extends therefrom and is connected at its other end to a bell crank lever 29 fulcrumed at 30 on a bracket 31 bolted at 32 to the breast beam. The opposite arm of the bell crank lever extends beneath a portion of a latch 33 pivoted at 34 on a transmitter 35 extending transversely over the breast beam and in turn pivoted at its forward end 36 to an arm 37 secured to and upstanding from a starter rod or 40 shaft 38 journalled in bearings 39 at the front of the breast beam. The starter rod illustrated is of the type commonly employed for connection with and for actuating a means for automatically replenishing the filling. In the construction thus illustrated, when the feeler slips laterally, owing to 45 substantial exhaustion of the filling in the working shuttle and carries laterally with it the controller 20, the rod 28 is moved laterally rocking the bell crank lever 29 and lifting the latch 33 into the path of the 50 constantly vibrating weft hammer 40. Consequently the transmitter 34 is carried forwardly rocking the starter rod 38 and thus initiating the desired change in the opera-

tion of the loom; such, for example, as the replenishment of the weft.

With the mechanism thus far described it will be seen that the feeler tip is struck by the mass of filling on the working filling carrier at each detecting beat or under usual conditions at each alternate beat-up of the lay and this continual banging of the working filling against the feeler tip and the continual reciprocation of the feeler rod goes on as long as the loom is in operation. One feature of the present invention, as already pointed out, is for the purpose of eliminating this continual action and thus minimizing the wear of the mechanism and the strain upon the filling.

In other words, the feeler is to have periods of activity and periods of inactivity during weaving with the same supply of filling in the shuttle, and in order that the feeler may not contact with the filling, even lightly, during its period of inactivity, the present invention contemplates that it be withdrawn in a direction away from its feeling position to assume its position of inactivity and be held in such position until released to its shorter period of activity.

In the construction illustrated, as a preferred form of embodiment of this feature of the invention, a detent device is provided which acts to engage the feeler and hold it against rearward movement during its periods of inactivity. This detent device is mounted on the feeler support so as to be bodily movable forwardly and rearwardly. When the feeler is released from the detent device so as to co-operate in a normal manner with the filling in the active shuttle, the detent device moves rearwardly and if the filling is not depleted to a predetermined amount or to a point where it is approaching substantial exhaustion the feeler is forced into re-engagement with the detent device and the detent device is then moved bodily forwardly thus carrying the feeler to a position where it remains in its unreleased or inoperative position well out of contact with the filling.

In the construction illustrated the rearward and forward bodily movement of the 115 detent device is provided by means of a detent carrier 41. The rearward end of the carrier rests and slides upon the upper surface of a rocker block 42 journalled at 43 in lugs 44 upstanding from the cap plate 19. A guide rod 45 projects forwardly from the 120 rocker block 42 and is provided at its forward end with a collar 46 adjustably secured to it by a set screw 47. A block 48 is rigidly and longitudinally adjustably secured to the bottom of the carrier by means of a set screw 49 passing through a slot 50 in the carrier. This block is apertured to fit and slide upon the guide rod 45. A helical spring 51, surrounding the rod between the 125

block 48 and the adjustable collar 46, acts to project the carrier rearwardly. The detent device proper is in the form of a pawl 52 pivoted at 53 to the block 48 and yieldingly held in depressed or engaging position by a helical spring 54.

It will thus be seen that the present invention provides a detent for engagement with a part connected to the feeler when the feeler is moved frontwardly by a working supply of filling in the shuttle on a detecting beat, and means are provided to move or withdraw the detent, and consequently the feeler, away from feeling position to assume its position of inactivity, for an interval of time, and then release the feeler to the performance of its feeling function.

At the forward end of the feeler support 20 there is mounted for rotary movement a double cam or detent controller. The members of this cam are conveniently formed upon the upper surface of a ratchet wheel 55. This ratchet wheel is seated on a friction washer 55^a on the upper surface of a supporting arm 56 of a bracket 57 bolted at 58 to the support 9 and is journalled upon a stud 59 which may be a continuation of, or in axial alinement with, the swiveled portion 16 of the guide 15. One cam member is formed by the upper surface 60 of a projection 61 from the face of the ratchet wheel. The other cam member is formed by the inner surface 62 of an irregular shaped flange 63 projecting from the face of the ratchet wheel.

These two cams control the movement of the carrier and, consequently, of the detent device. The forward end of the carrier 41 has secured thereto and depending therefrom a follower 64 in the form of a cylindrical stud rounded-off at the bottom. The engagement of the side of this follower with the cam surface 62, in co-operation with the spring 51, imparts the required forward and rearward movements to the carrier. The engagement of the lower end or bottom of this follower with the upper surface of the ratchet wheel and the cam surface 60 in co-operation with a helical spring 65 seated between the rocker block 42 and the cap plate 19 imparts an up and down tipping movement to the carrier to effect the release of the detent device.

The double rotary cam is given its rotary movement in any suitable manner from any moving part of the loom. In the construction illustrated such movement is secured by a pawl and ratchet mechanism operated by the lay. For this purpose the pawl-carrying arm 66 is journalled on the stud 59 and at its free end has pivoted thereto a pawl 67 held by a helical spring 68 in engagement with the teeth of the ratchet wheel 55. A slide block 69, journalled on the lower end

of the stud 70 carrying the pawl, is mounted in a slot in the top of a block 71 adjustably secured by a set screw 72 to a plunger rod 73. This plunger rod is preferably mounted to slide rectilinearly in line with the path 70 of movement of the lay. It is shown as mounted at its rear end in one of the lugs 44 and at its forward end in a lug 74 upstanding from the bracket 57. A helical spring on the rod, abutting the lug 74 and the block 71, acts to project the plunger rod rearwardly and a collar 75, adjustably secured on the plunger rod by means of a set screw 76, limits the rearward movement by engagement with the lug 44.

The plunger rod 73 at its rearward end is provided with a suitable elastic tip or buffer 77 and, as shown, is adapted to come into contact with the front shuttle wall carried by the lay. Consequently, upon each beat-up of the lay the plunger is moved forwardly to an extent determined by the position of the collar 75 and, consequently, moves the pawl 67 and rotates the ratchet wheel 55 one or more teeth.

The operation of the mechanism will now be apparent. During the main portion of the periods, when the feeler is in its inoperative position, the parts are generally shown in Fig. 7. Under these conditions the detent carrier 41 is held in its retracted position by the follower 64 being in engagement with the circular portion of the cam surface 62 which constitutes three-fourths of the length of the cam. The detent 52 is held downwardly by its spring 54 in engagement with one of the teeth 78 on the slide 22 secured to the feeler so that the feeler is held in its retracted position. Thus both the springs 51 and 25 are compressed. In this position the feeler is locked so far forwardly that its tip is well out of possibility of contact with the filling in the working shuttle when the lay beats up. The plunger 73 is pushed forwardly by the lay upon each beat-up and thus gradually through the pawl and ratchet mechanism rotates the double cam. Finally the cam 60, riding under the follower, raises the forward end of the detent carrier 41, tipping it about its axis 43 and compressing the spring 65. As the high part of the cam 60 passes under the follower 64 the detent carrier is tipped sufficiently to release the detent 52, which is limited in its movement with respect to the block 48 by the stop 79, from the teeth 78 and thus allow the feeler to be projected by the spring 25 to its rearward position. The feeler now co-operates in the normal manner with the filling in the active shuttle. The parts now are in the general position shown in Fig. 3. At or immediately after the release of the feeler the cam 60 rides from under the follower 64, the carrier is tipped by the spring 65 to its normal hori- 130

zontal position, and the extreme point of the face cam 62 comes opposite the follower 64 allowing the carrier 41 to be projected rearwardly by the spring 51. If now 5 the filling has reached the required point of substantial exhaustion the feeler will be given its initiating movement, in this case the "side slip" movement, and will through suitable means, such as, the controller 20 10 and connections hereinbefore described, set into operation the mechanism for initiating a change in the operation of the loom, such as, the filling replenishment. If however, as is usually the case, the filling has not been 15 depleted to the required extent there is no initiating movement or "side slip" of the feeler and it is forced forwardly by the filling on the beat-up and its teeth 78 re-engage with the detent 52 which detent, it will be 20 remembered, is now in its rearward position. After the feeler has thus re-engaged with the detent the parts are generally in the position shown in Fig. 4. But it will be remembered that the double cam is being 25 steadily rotated and immediately this re-engagement of the feeler with the detent takes place the cam face 62 adjacent the extreme point 80 passes the follower 64 and draws the carrier and with it the detent device 30 bodily into its forward position. Hence the feeler is immediately brought into position where it is well out of contact with the filling.

Applicant believes himself to be the first 35 in the art to provide a feeler mechanism for looms with means for moving or withdrawing the feeler away from its feeling position and holding it there during the period of inactivity of the feeler and to release the feeler at intervals to perform its feeling function so that during the periods of inactivity of the feeler it will not engage the filling, even though the diameter of the filling presented to the feeler may vary.

Having thus described the invention what 45 is claimed as new and desired to be secured by Letters Patent, is:

1. A feeler mechanism for looms comprising a feeler support, a feeler movably mounted on the support, means for yieldingly projecting the feeler rearwardly, a detent device acting to engage the feeler and hold it against rearward movement, means acting at regular intervals to release the feeler from the detent device and thus allow the feeler to be projected rearwardly to co-operate in normal manner with the filling in the active shuttle, the other cam member acting upon or after the release of the feeler from the detent device to release the carrier and allow it to move rearwardly whereby, if the said filling is not depleted to a predetermined amount, the feeler will be moved by the filling into re-engagement with the detent device and means to restore the detent device to retracted position after it has been re-en-

gaged by the feeler whereby the feeler, when in unreleased or inoperative position, is held well out of contact with the filling.

2. A feeler mechanism for looms comprising a feeler support, a feeler movably mounted on the support, means for yieldingly projecting the feeler rearwardly, a detent device acting to engage the feeler and hold it against rearward movement, means acting at regular intervals to release the feeler from the detent device and thus allow the feeler to be projected rearwardly to co-operate in normal manner with the filling in the active shuttle, a carrier for the detent device movably mounted on the support, 75 means for yieldingly projecting the carrier rearwardly, means acting to release the carrier upon or after the release of the feeler by the detent device whereby, if the said filling is not depleted to a predetermined amount, the feeler will be moved by the filling into re-engagement with the detent device and means acting after the feeler has re-engaged the detent device to retract the carrier and hold it in retracted position 80 whereby the feeler, when in unreleased or inoperative position, is held well out of contact with the filling.

3. A feeler mechanism for looms comprising a feeler support, a feeler movably mounted on the support, means for yieldingly projecting the feeler rearwardly, a detent device acting to engage the feeler and hold it against rearward movement, a carrier for the detent device mounted on the support for 95 forward and rearward movement and for tipping movement, means for yieldingly projecting the carrier rearwardly, a double rotary cam, a ratchet wheel for rotating the cam, a pawl carrier and pawl-co-operating 100 with the ratchet wheel, means for moving the pawl carrier thereby to effect the rotation of the cam, one cam member acting at a predetermined point in its rotation to tip the carrier and release the feeler from the 105 detent device and thus allow the feeler to be projected rearwardly to co-operate in normal manner with the filling in the active shuttle, the other cam member acting upon or after the release of the feeler from the detent device to release the carrier and allow it to move rearwardly whereby, if the said filling is not depleted to a predetermined amount, the feeler will be moved by the filling into re-engagement with the detent device, the 110 said other cam member then acting after the feeler has re-engaged the detent device to retract the carrier and hold it in retracted position whereby the feeler, when in unreleased or inoperative position, is held well out of contact with the filling.

4. A feeler mechanism for looms comprising the construction in claim 3 in which the one cam member is formed by the upper 115 surface of a projection from the face of the 120

ratchet wheel and in which the other cam member is formed by the inner surface of a flange projecting from the face of the ratchet wheel.

- 5 5. A feeler mechanism for looms comprising a feeler to co-operate intermittently with the filling in the active shuttle and thereby effect a change in the operation of the loom when substantial exhaustion of filling is detected, means to engage and hold the feeler in retracted position, means acting at regular intervals to release the feeler from the engaging means and allow it to co-operate in normal manner with the filling, means 10 acting, until substantial filling exhaustion is approached, upon each release and temporary co-operation of the feeler with the filling first to move the engaging means into projecting position then to restore the feeler 15 into engagement with the engaging means and then to move the feeler and the engaging means into retracted position whereby the feeler, when in unreleased or inoperative position, is held well out of contact 20 with the filling.

6. A feeler mechanism for looms comprising the construction defined in claim 1 in which the feeler is movably mounted on the support both to move forwardly and rearwardly and also laterally, the said lateral movement taking place when the filling is sufficiently depleted to allow the feeler to slip on the filling carrier.

7. A feeler mechanism for looms comprising the construction defined in claim 3 in which the feeler is mounted to move forwardly and rearwardly on the support in a path at an acute angle to the path of movement of the pawl carrier and in which the 30 feeler is also mounted to move laterally on the support, the said lateral movement taking place when the filling is sufficiently depleted to allow the feeler to slip on the filling carrier.

- 40 8. A feeler mechanism for looms comprising the construction defined in claim 3, together with means for adjusting the movement of the pawl carrier to effect a predetermined degree of rotation of the cam.

- 50 9. In a loom, the combination of a feeler to detect substantial exhaustion of the filling in the shuttle and thereupon initiate replenishment of filling, a feeler withdrawing and holding device to withdraw the feeler from 55 cooperative relation with the filling and maintain it at rest, and means to operate said device to free the feeler at intervals during weaving with the same supply of filling in the shuttle that the feeler may have periods of activity and periods of inactivity with respect to the same filling in the shuttle.

- 60 10. In a loom, the combination of a yieldingly sustained feeler to cooperate with the filling in the shuttle and bring about a

change in the operation of the loom when substantial exhaustion of filling is detected, a feeler retracting and holding device to withdraw the feeler and hold it in retracted position, means for operating the feeler re- 70 tracting and holding device to free the feeler at intervals and then withdraw and hold the feeler again in retracted position when a working supply of filling is in the shuttle on a detecting beat that the feeler may have 75 periods of activity and periods of inactivity during weaving with the same supply of filling.

11. In a loom, the combination of a feeler, means for drawing the feeler frontwardly 80 out of cooperative relation with the filling and holding it at rest for a period of time and then releasing it to the performance of its feeling function, and mechanism for operating said means that the feeler may have 85 periods of activity and be withdrawn into a position of inactivity at intervals during weaving with the same supply of filling in the shuttle.

12. A feeler mechanism for looms, comprising, in combination, a feeler, a spring normally tending to move the feeler to rearward feeling position, a feeler withdrawing and holding device to move the feeler frontwardly in opposition to said spring and hold it in inoperative relation to the filling and to release the feeler periodically, and operating means for the feeler withdrawing and holding device to cause said device to free the feeler at intervals to the action of its 90 spring and then withdraw and hold the feeler at rest for another period of inactivity during weaving with the same supply of filling in the shuttle.

13. A feeler mechanism for looms, comprising, in combination, a feeler mounted to enter the shuttle and detect substantial exhaustion of the filling and thereupon initiate replenishment of filling, a detent to engage a part connected to the feeler when 100 the feeler is moved frontwardly by a working supply of filling in the shuttle on a detecting beat, means acting to move the feeler frontwardly an additional amount beyond the reach of the filling on detecting beats 110 and hold it in inoperative position, and means for freeing the feeler at intervals that the feeler may have periods of activity and periods of inactivity during weaving with the same supply of filling in the shuttle. 115

14. A feeler mechanism for looms, comprising, in combination, a feeler mounted to enter the shuttle and detect substantial exhaustion of the filling and thereupon initiate replenishment of filling, a detent to engage 120 a part connected to the feeler when the feeler is moved frontwardly by a working supply of filling in the shuttle on a detecting beat, a detent controller to move the detent frontwardly and further move the feeler 125 130

away from feeling position and trip the detent at intervals, and means for actuating the detent controller.

15. In a feeler mechanism for looms, the combination of a feeler mounted to enter the shuttle in a direction inclined to the longitudinal axis of the shuttle and detect substantial exhaustion of the filling and thereupon effect replenishment of filling, means to move the feeler in a direction away from feeling position when it is moved frontwardly by a working supply of filling in the shuttle and to hold it in such position of inactivity for an interval of time and then release the feeler for movement to feeling position, and operating mechanism for said means that the feeler may have short periods of activity and longer periods of inactivity during weaving with the same supply of filling in the shuttle.

16. In a loom, the combination of a feeler, a detent to engage a part connected to the feeler when the latter is moved by a working supply of filling on a detecting beat, a detent controller having a part to move the detent bodily in a direction to carry the feeler away from feeling position and a part to trip the detent and free the feeler, said parts being constructed and arranged to act alternately at intervals, and means for actuating the detent controller.

17. In a loom, the combination of a feeler, a detent, a detent controller comprising a part for causing the detent to move the feeler away from feeling position when the detent is operatively related thereto and a part to effect release of the feeler from the detent at intervals, and means for operating the detent controller.

18. In a feeler mechanism for looms, the combination of a feeler to detect substantial exhaustion of filling in the shuttle and thereupon initiate replenishment, means for moving the feeler frontwardly beyond the reach of the filling on detecting beats and for holding it at rest for a period of time out of cooperative relation with the filling and releasing it at intervals for the performance of its feeling function that the feeler may have periods of activity and inactivity during weaving with the same supply of filling in the shuttle.

19. In a feeler mechanism for looms, the combination of a feeler to detect substantial exhaustion of the filling in the shuttle and thereupon initiate replenishment of filling, a detent for determining the active and inactive condition of the feeler, and a detent controller to control movements of the detent into three positions, one to release the

feeler, another to engage a part connected to the feeler, and another to move the feeler in a direction away from feeling position.

20. In a feeler mechanism for looms, the combination of a feeler to detect substantial exhaustion of the filling in the shuttle and thereupon cause replenishment of filling, a detent for holding the feeler in a frontward position, means for causing the detent to move the feeler further frontward beyond the reach of the filling on detecting beats, and means for tripping the detent at intervals that the feeler may have periods of activity and periods of inactivity during weaving with the same supply of filling in the shuttle.

21. A feeler mechanism for looms, comprising, in combination, a feeler mounted for yielding movement to feeling position to detect substantial exhaustion of the filling in the shuttle and thereupon cause replenishment of filling, a movable detent carrier, a detent yieldingly mounted on the detent carrier to engage a part connected to the feeler, a detent controller, and means for actuating the controller to cause the detent to withdraw the feeler frontwardly beyond the reach of the filling on detecting beats and hold it during periods of inactivity and then release the feeler to its feeling function for periods of activity during weaving with the same supply of filling in the shuttle.

22. In a feeler mechanism for looms, the combination of a feeler, means for moving the feeler to an inoperative position beyond the reach of the filling in the shuttle on detecting beats that it may be held during its periods of inactivity out of contacting relation with the filling, and means for freeing the feeler at intervals that it may have periods of activity and periods of inactivity during weaving with the same supply of filling in the shuttle.

23. A feeler mechanism for looms, comprising, in combination, a feeler, means for causing movement of the feeler to an inoperative position beyond the reach of the filling in the shuttle on detecting beats, means acting to hold the feeler in such inoperative position during periods of inactivity that it may not engage the filling, and means for freeing the feeler at intervals that it may have periods of activity and periods of inactivity during weaving with the same supply of filling.

In testimony whereof, I have signed my name to this specification.

HARRY A. DAVIS.
